UNITED STATES PATENT OFFICE.

WILLIAM STEVENSON WESTON, OF COLUMBIA, SOUTH CAROLINA, ASSIGNOR TO WESTON AND BROOKER, ENGINEERS, OF COLUMBIA, SOUTH CAROLINA, A PARTNERSHIP COMPOSED OF W. S. WESTON, T. I. WESTON, AND B. O. BROOKER.

GYRATORY CRUSHING MACHINE.

Application filed March 29, 1921. Serial No. 456,663.

To all whom it may concern:

Be it known that I, WILLIAM S. WESTON, a citizen of the United States, and residing at Columbia, Richlands County, State of 5 South Carolina, have invented certain new and useful Improvements in Gyratory Crushing Machines, of which the following is a specification.

The present invention relates to gyratory 10 crushers of the kind usually used for crushing rock and ores, to obtain materials to be used in the building, cement, and other related industries. The invention relates particularly to the type of gyratory crusher 15 having a vertical shaft pivotally mounted at one end in a stationary frame, its other end being journaled within a rotatable sleeve or eccentric, the axis of the shaft being eccentric to the axis of the sleeve and having 20 power means for rotating the sleeve so that the shaft has a gyratory motion which enables the crushing cone or head secured thereon at a point intermediate the ends of the shaft, to exert a powerful crushing force 25 against the stone passing downwardly between the crushing head and the crushing hopper surrounding the same and secured in the casing, this hopper constituting a stationary cylindrical crushing jaw and the 30 crushing cone constituting a movable crushing jaw of the machine.

Gyratory crushing machines of this class which have heretofore been designed or suggested have usually been constructed with 35 the shaft pivotally supported at its upper end and with rotatable eccentric sleeve at its lower end, this sleeve being driven by gearing, belts, or pulleys, from suitable power means. The type of gyratory crushing machine in which the gyratory shaft is pivotally supported at its base and the rotatable eccentric at the top has not come 40 into use owing to the practical difficulties of design met with, such as the difficulty 45 of properly lubricating the eccentric sleeve and the difficulty of keeping the dust generated in the crushing operation out of the driving mechanism and out of the lubricating system. Where the gyratory shaft 50 is pivoted at its upper end and driven at its lower end trains of gears, or systems of sheave and ropes have been found necessary to apply the power and such mechanism must necessarily be contained within a small

space, rendering the driving mechanism 55 relatively complicated and causing unnecessary frictional losses due to the multiplication of parts. Due to the great frictional losses the bearings must be frequently replaced. 60

Furthermore, in former types of gyratory crushers in which the shaft is pivoted at the top and which are particularly adapted to crush the aggregate of a previous crush, that is, one which serves as a secondary or reducing machine, unnecessary power is used due to great frictional resistance, and the parts are subjected to excessive strain, because of the fact that the crushing action of the jaws is greatest at their lower 70 ends and least at their upper ends due of course to the fact that the eccentric is located at the lower end of the shaft and the motion of the shaft becomes less and less as the distance from the eccentric increases. 75 Theoretically these conditions should be reversed, that is, the crushing motion should be greatest at the entrance to the crushing jaws and least where the rock escapes. 80

Another objection to such machines heretofore designed resides in the large size of the eccentric sleeve found necessary. Increasing the size of the eccentric has cut down the speed at which the shaft can be gyrated on account of the practical requirements of bearing speeds and the limitation of gear speeds. 85

In addition the machines of the prior art have usually been so mounted upon their foundations that the actual crushing action 90 takes place at an elevation considerably above the point of support, that is, above the point where the frame or casing of the machine is secured to the foundations. This results in an excessive vibration of the entire machine. 95

Furthermore, the location of the driving mechanism adjacent the base of the shaft exposes it to clouds of dust and grit which result from the crushing operation. Usually 100 such driving mechanism is positioned below the foundation level and the opening for feeding the rock into the machine. In such exposed location the driving gearing or other means must be carefully surrounded by or enclosed within a substantially dust-proof casing, rendering the machine 105 more expensive and complicated and render-

ing the moving parts of the driving mechanism less accessible.

In accordance with this invention a gyratory crushing machine is provided in which the shaft is driven by mechanism located adjacent its top. This mechanism comprises an eccentric sleeve surrounding the shaft, a swivel bearing supporting the sleeve in such a manner that it may be freely rotated while at the same time may change the direction of its axis to compensate for slight inaccuracies in construction and subsequent bending of the gyratory shaft in crushing hard materials, and means for driving the eccentric directly without the usual intermediate gearing. A novel oiling system is provided for maintaining the bearing surfaces of the eccentric and its supporting bearing properly lubricated at all times. The casing of the crusher is adapted to be supported upon suitable foundations, the points of support being substantially in the same horizontal plane as the crushing jaws so that the shock and strain incident to the crushing operation is transmitted horizontally directly into the foundations. The crushing hopper is formed in several sections instead of a single piece and may be quickly and easily assembled in position and removed or reversed. The crushing cone extends upwardly above the upper edge of the crushing hopper a substantial distance and above the level of the entrance through which the rock is supplied, and this extension serves as a stirring member for aligning the stones to more freely enter between the crushing jaws, and to more evenly distribute them around the crushing cone.

The improved crusher has therefore a number of advantages over crushers of this class heretofore known. As the eccentric is directly driven either by an electric motor or by a pulley, trains of gears, etc. are not necessary, with the resulting loss of power which their use involves. The crushing movement of the jaws complies more nearly with theoretical requirements inasmuch as the shaft is pivotally mounted at its lower end and driven from its upper end so that the lateral or crushing movement of the movable jaw or cone is much greater at its upper end than at its lower. The eccentric being relatively small and directly driven may rotate at a much higher speed than other eccentrics, thus increasing the production of the machine. Vibration is decreased to a minimum due to the manner in which the casing is supported. The machine is so designed that it is practically impossible for dust to contact with any wearing surfaces, and the various moving parts are arranged to be readily accessible for the purpose of inspection and repair. The novel oiling system whereby the eccentric is continuously lubricated involves

circulation of a relatively large body of oil in a closed circuit which includes the bearing surfaces of the eccentric and into which circuit no dust or grit may enter.

The construction of the crushing hopper in sections which may easily be taken apart, enables it to be removed and to be reversed whereby its useful life may be greatly prolonged, and the extension upwardly of the crushing cone above the crushing hopper and feed opening results in a much more even feed of material between the crushing jaws, the individual stones being both properly aligned by the stirring movement of the cone, and the stone being more evenly distributed around the hopper.

To one skilled in the art still other advantages will be apparent from the disclosure of one embodiment of the invention in the following description and in the accompanying drawings.

In the drawings:

Figure 1 is a side elevation of the crusher as mounted upon a foundation, partly broken away to show the interior construction;

Figure 2 is a side elevation of the eccentric sleeve;

Figure 3 is a longitudinal section of the same;

Figure 4 is a section on line 4—4 of Figure 2;

Figure 5 is a section through a portion of the casing showing the crushing hopper;

Figure 6 is a section on line 6—6 of Figure 5;

Figure 7 is a side elevation partly broken away, of the upper portion of the crusher, the eccentric being arranged to be directly driven by an electric motor instead of by a pulley.

The casing of the crusher has three portions; a main portion 10, which is substantially cylindrical in shape, and has external annular flanges 11 and 12 at its upper and lower ends respectively; a bottom portion 13 in the form of a spider having an annular ring portion 14 adapted to be bolted to the flange 12; and an annular cap or ring 15 adapted to be secured by bolts to the flange 11. The casing 10 has two diametrically oppositely positioned openings 16 which serve as feed openings, and has a cylindrical surface 17 directly below the lower edges of these openings to which the crushing hopper is secured. This hopper, as clearly illustrated in Figures 5 and 6, comprises four portions, two main portions 18 and 19 and two minor portions 20 and 21 which are formed as wedges. Each of the four portions of the crushing hopper has a backing of metal such as zinc, as indicated at 22 and these portions are so formed as to fit closely within the cylindrical portion of the casing when assembled. The wedges

20 and 21, when forced into position, cause the hopper to be tightly wedged in position but these wedges may be withdrawn and the hopper reversed in position whenever 5 desired, that is, the hopper may be turned upside down and re-assembled so that the wear due to the crushing action may be evenly distributed, and a maximum length of life of the hopper insured.

10 The spider 13 has a plurality of legs 23 preferably three by means of which its central cylindrical portion 24 is suspended from the ring 14. This cylindrical portion 24 has a cylindrical axial aperture 25 therein, the 15 lower end of which is closed by a cap 26. A bearing sleeve 27 serves as a lining for the upper end of the cylindrical aperture 25 and a flat disk or plate 28 is positioned in the lower end of this aperture which flat plate 20 overlies the upper end of an adjusting screw 29 which may be utilized to adjust the position of plate 28 within the cylinder 25. The sleeve 27 tapers upwardly interiorly and fits closely around, at its upper end, a cylindrical cap 30, the lower end of which rests upon the disk 28 and which has an axial conical socket 31 therein to receive the conical lower end of the gyratory shaft 32. As the shaft 25 gyrates the cap 30 also has a gyratory motion, to have a full bearing against sleeve 27 on the side which bears the pressure. A dust excluding ring 24' slidably rests on the upper surface of member 24 and moves laterally with the cap and shaft. This ring 30 prevents dirt and dust from penetrating into the recess containing cap 30. Shaft 32 extends substantially vertically of the machine and its upper end extends into a cylindrical aperture 33 of sleeve 34 which is rotatably 40 supported in a bearing B mounted in the top of the casing. The cylindrical aperture 33 is eccentric relative to the cylindrical outer surface of sleeve 34 so that the sleeve has a thin walled side, as shown in Figure 1.

45 The bearing B has a cylindrical central portion 35 provided with a cylindrical axial recess to receive the sleeve 34 and an outer shell 36 having an external spherical bearing surface which rests against concentric spherical bearing surfaces formed on the inside of the cap 15 and the adjacent portion of the upper end of cylinder 10. The bearing B is free to swivel therefore relatively to the casing, having in reality a ball and 50 socket connection thereto, but to prevent rotation in the horizontal plane of the bearing relatively to the casing a key 37 is provided, this key having its shank extending into a recess in the shell 36 and its outer end extending into a groove formed partially in the cap 15 and partially in the cylinder 10. This key is rotatable about its horizontal axis and does not hinder the swivel action of the bearing in its seat.

55 The sleeve 34 is supported at its lower end upon an annular shoulder 38 on the inner surface of the axial opening through the cylindrical portion 35 of the bearing. The inner and outer walls thereof on the thin walled side are provided with a series of 55 inclined grooves 39 and 40 respectively, these grooves extending substantially half way around the sleeve. A small conduit or port 41 may connect the lowermost groove 70 of the outer series with the inner surface of the sleeve. A second conduit 42 formed therein brings the interior of the sleeve into communication with an annular chamber 43 in the bearing B, which chamber communicates in turn, by means of a duct or conduit 75 44, with the interior of a large deep oil receptacle or container 45 firmly fixed on shaft 32 below the bearing. The wall of the container 45 extends a considerable distance 80 above the lower end of the bearing sleeve 34 and its upper edge is inturned, as at 46, the diameter of the opening across the top of the container being as small as possible, in view of the necessary clearance which must be left between its edge and the outer surface of the cylindrical portion 35 of the bearing, due to the fact that relative movement of the container 45 and bearing B occurs in the operation of the machine, the container moving with the shaft 32 and the bearing remaining stationary, being supported by the casing.

85 A pulley 47 is rigidly secured to the upper end of the sleeve or eccentric 34 and is adapted to receive a belt driven by suitable power means to cause the rotation of the eccentric and the gyration of the shaft. When in operation the shaft will gyrate about a point 48, which is the point of intersection of the axis of the shaft with the 90 plane of the upper end of bearing 27. The belt bearing surface of pulley 47 is horizontally opposite the bearing surfaces of bearing B and eccentric 34, the exact arrangement being such that the resultant of the 95 forces exerted by the belt on the pulley, by the bearing B on the casing, and by the sleeve 34 on the shaft and on the bearing B, all lie substantially in the same plane, thereby avoiding all tendency of the moving parts 100 to bind and considerably reducing the frictional resistance of the machine. The inner wall 49 of the shell 36 is cylindrical and positioned between this wall and the outer wall of the cylindrical portion 35 of the bearing 105 is an annular dust cap 50, the edges of which are in close proximity to the two concentric cylindrical walls referred to, to prevent dust from passing around the upper edge or container 45 and becoming mixed with the oil. The lower surface of dust cap 50, that is, the 110 surface which abuts against the upper edge of the oil container 45, is spherical, the center of the spherical surface being the point 115 48. The upper edge of container 45 is pref- 120

125

130

erably formed with a concentric spherical surface, the arrangement being such that relative movement of the container 45 and dust cap 50 opens no crack between these 5 elements through which dust may enter the oil chamber.

The upper end of the cylindrical interior of the eccentric 34 is closed by a cap 51 which is readily removable for the insertion 10 of lubrication or for the purpose of examination.

Supported on shaft 32 horizontally opposite the crushing hopper is a cone 52 which in turn supports the movable crushing jaw 15 or cone 53. This cone has a separate cap portion 53' which extends a considerable distance above the upper edge of the crushing hopper and above the lower edge of the feed opening 16. This upper portion constitutes a stirring portion which first contacts with the stone which enters through the feed openings and distributes it around evenly in a circle before it passes between the crushing jaws, and also serves to align 20 the larger rocks or to place them on edge vertically.

An oil cup 54 secured to the casing is connected by means of a pipe 55 to the interior of cylinder 24 and lubricant may be easily 25 inserted into the cylinder by this means to lubricate the lower end of the gyrating shaft.

In the operation of the crusher the sleeve or eccentric 34 is rapidly rotated by power applied to the pulley 47 thereby giving the 30 crushing cone 53 a gyratory motion in a well known manner, and crushing rocks or ore which pass through the machine between the crushing jaws. The lower end of eccentric 34 is always submerged in oil and the 35 inclined grooves 39 and 40 lift this oil upwardly continuously to be collected in the chamber 43 and to be returned through duct 44 to the oil chamber. These grooves 39 and 40 are formed in the thin walled side of the eccentric which side is under little or no strain due to the crushing action. The thick 40 walled side of the eccentric takes practically all of the strain as it is the wedge which forces the shaft from side to side. The 45 grooves do not therefore cut down the area of useful bearing surface of the eccentric. The oil is continually circulated and no dust can enter the oil chamber. The cap 51 may be removed at any time even when the machine is operated and additional oil added. In case it is necessary to vertically adjust 50 the movable crushing jaw by means of screw 29 the dust cap 50 slides freely upwardly or downwardly as the case may be, without having its efficiency as a dust guard impaired.

In case the cap 30 becomes worn the spider 13 and the shaft may be dropped and removed and cap 30 removed from the end of 55 the shaft by inserting a screw bolt through

the threaded opening 56 in the bottom of the cap, to force it from the shaft. A new cap may be then placed on the shaft and the shaft returned to position in the machine. The crushing action takes place practically 70 in the same plane in which the machine is supported so that crushing shocks are conveyed directly to the foundations, thereby largely eliminating harmful vibration of the machine. 75

In Figure 7 I have illustrated an electric motor 60 mounted upon the top of the casing and having its shaft directly connected to the eccentric. This mode of operating the crusher involves no intermediate connections 80 such as a belt or pulley between the source of power and the eccentric and is especially advantageous when electric power is available.

Other modifications and changes may be 85 made by one skilled in the art to the design and arrangement of the parts of the machine within the scope of the invention, which is not limited to the embodiment disclosed.

Having thus described my invention what 90 I claim as new and desire to secure by Letters Patent is:

1. A gyratory crusher including, in combination, a frame, a shaft having one end pivotally supported in said frame, a rotatable sleeve having an eccentric aperture to receive the other end of the shaft whereby rotation of said sleeve will cause gyration of the shaft, a bearing member mounted on the frame and free to swivel relatively thereto, 95 100 for supporting said rotatable sleeve, and means for rotating said sleeve.

2. A gyratory crusher including, in combination, a frame, a shaft having one end pivotally supported in said frame, a bearing member mounted on the frame and free to swivel relatively thereto, said bearing member having an axial cylindrical opening therethrough and a shoulder in said opening near the lower end thereof, a rotatable sleeve mounted in the axial opening of the bearing and resting on said shoulder, said sleeve having an eccentric aperture to receive the free end of the shaft whereby rotation of said 105 110 sleeve will cause gyration of the shaft, and means for rotating said sleeve.

3. A gyratory crusher including, in combination, a frame, a shaft having one end pivotally supported in said frame, a bearing member mounted on the frame, said member and frame having cooperating spherical bearing surfaces whereby said bearing may have swivel movement relatively to the frame, a sleeve rotatably supported by said bearing, the axes of said sleeve and bearing being coincident and said sleeve having an eccentric aperture to receive the free end of the shaft, and means for rotating the sleeve whereby the shaft may be given a gyratory 115 120 125 motion. 130

4. A gyratory crusher including, in combination, a frame, a cap removably secured to said frame, a spherical bearing surface being formed partly in said frame and partly in said cap, a bearing member having a spherical surface seating on the spherical bearing surface of said frame and cap, a rotatable sleeve mounted axially in said bearing and having an eccentric aperture 10 therein to receive the free end of the shaft, and means for rotating said sleeve.
5. In a gyratory crusher, in combination, a frame, a shaft having one end pivotally mounted in said frame, a bearing pivotally mounted in said frame, a sleeve rotatably supported in said bearing and having an eccentric aperture to receive the free end of the shaft, and means for rotating said sleeve to give the shaft a gyratory motion.
6. In a gyratory crusher, in combination, a frame having a spherical seating surface, a shaft having one end pivotally supported on said frame, a bearing member having a spherical surface seating on the spherical bearing surface of the frame whereby it may have a swivel movement relatively thereto, a rotatable member concentrically mounted in said bearing and having an eccentric aperture to receive the free end of the shaft, and means for rotating said member.
7. In a gyratory crusher, in combination, a frame, a shaft having one end pivotally supported in said frame, a bearing member having a ball and socket connection with said frame and provided with a central axial aperture, a member rotatably supported in said aperture and having an eccentric opening therein to receive the free end of the shaft, the cooperating bearing surfaces of the frame, bearing member, and rotatable member, being so positioned that the resultants of the bearing forces lie substantially in the same plane, and means for rotating said rotatable member.
8. In a gyratory crusher, in combination, a frame, a shaft having one end pivotally supported in said frame, a bearing member mounted in said frame to have swivel movement relatively thereto, a member rotatably supported axially in said bearing member and provided with an eccentric aperture to receive the free end of the shaft, a pulley rigidly connected to said rotatable member and having its belt bearing surface concentric with and opposite the bearing surfaces of the rotatable member.
9. In a gyratory crusher, in combination, a frame, a shaft having one end pivotally supported in said frame, a bearing member mounted in said frame to have swivel movement relatively thereto, a member rotatably supported axially in said bearing member and provided with an eccentric aperture to receive the free end of the shaft, a pulley rigidly connected to said rotatable member and having a belt bearing surface, the belt bearing surface of the pulley and the bearing surfaces of the rotatable member being so arranged that the resultants of the forces exerted on the pulley by the belt and by the rotatable member upon the bearing member and shaft lie substantially in the same plane.
10. In a gyratory crusher, in combination, a frame having a spherical bearing surface, a shaft having one end pivotally mounted in said frame, a bearing member having a spherical surface seating on the spherical surface of said frame and having an axial aperture, a member rotatably mounted in said aperture and provided with an eccentric opening to receive the free end of said shaft, a pulley rigidly secured to said rotatable member and having a belt bearing surface, the belt bearing surface of the pulley and the cooperating bearing surfaces of the frame bearing member and rotatable member, being so arranged that the resultants of the forces exerted respectively by a belt on the pulley, by the bearing member on the frame, and by the rotatable member on the shaft and bearing member, lie substantially in the same frame.
11. A gyratory crusher including, in combination, a vertical shaft adapted for gyratory motion, a bearing, a rotatable sleeve mounted in said bearing and having an eccentric aperture to receive the free end of the shaft, an oil containing receptacle mounted on said shaft and extending above the lower end of said rotatable sleeve so that the latter is submerged in oil, and means for rotating said sleeve.
12. A gyratory crusher including, in combination, a vertical shaft adapted for gyratory motion, a bearing, a sleeve rotatably mounted in said bearing and having an eccentric opening therein adapted to receive the free end of the shaft, said sleeve having an inclined groove in its outer surface, an oil containing receptacle mounted on the shaft the interior of which is in communication with said groove, and means for rotating said sleeve.
13. A gyratory crusher including, in combination, a vertical shaft adapted for gyratory motion, a bearing, a cylindrical member rotatably mounted in said bearing and having an eccentric cylindrical opening therein adapted to receive the free end of the shaft, said member having an inclined groove in its inner surface, an oil containing receptacle mounted on the shaft for feeding oil to the lower end of the rotatable member, and means for rotating said member.
14. A gyratory crusher including, in combination, a shaft adapted for gyratory movement, a cylindrical member supported

for rotation about its axis, and provided with an eccentric cylindrical opening to receive the free end of the shaft, said member having an inclined groove in its inner surface and an inclined groove in its outer surface, an oil containing receptacle mounted on the shaft and extending above the lower end of the cylindrical member whereby said lower end is submerged in oil, and means for rotating said member.

15. A gyratory crusher including, in combination, a vertical shaft adapted for gyratory motion, a bearing, a sleeve rotatably mounted in said bearing and having an eccentric cylindrical opening therein adapted to receive the free end of the shaft, said sleeve having a plurality of inclined grooves on one of its bearing surfaces, an oil containing receptacle mounted on the shaft the interior of which is in communication with the lower groove of the series, and means for rotating said sleeve.

16. A gyratory crusher including, in combination, a vertical shaft adapted for gyratory movement, a bearing, a sleeve rotatably mounted in said bearing and having an eccentric opening therein to receive the free end of the shaft, said sleeve having an inclined groove on the outer surface of its thin-wall side, an oil containing receptacle mounted on the shaft the interior of which is in communication with the said groove, and means for rotating the sleeve.

17. A gyratory crusher including, in combination, a vertical gyratory shaft, a bearing, a sleeve rotatably mounted in said bearing and having an eccentric opening therein to receive one end of the shaft, said sleeve having a plurality of inclined grooves on the inner surface of its thin-wall side, an oil containing receptacle mounted on the shaft the interior of which is in communication with the lower groove of the series, and means for rotating the sleeve.

45. 18. A gyratory crusher including, in combination, a vertical shaft adapted for gyratory movement, a bearing, a sleeve rotatably mounted in said bearing and having an eccentric opening therein adapted to receive the free end of the shaft, an oil containing receptacle mounted on the shaft in which the lower end of the sleeve is submerged, and oil grooves in the bearing surface of the sleeve and in the bearing member whereby oil may be circulated in a closed circuit from the oil receptacle, along said bearing surface, and back to the oil receptacle.

19. A gyratory crusher including in combination, a frame, a crushing cone movably supported in said frame, and a crushing hopper surrounding said cone and secured to the frame, said hopper being formed in four sections, two of said sections being wedge shaped with their longitudinal axes vertically disposed, and one of said wedges

being upwardly directed and the other downwardly directed.

20. A gyratory crusher comprising in combination, a vertical gyratory shaft, an eccentric sleeve for gyrating the shaft and means for lubricating said sleeve including an oil receptacle fast on said shaft and surrounding the lower end of the sleeve.

21. A gyratory crusher comprising, in combination, a shaft supported at one end for gyratory motion about a point, a rotatable eccentric sleeve for imparting gyratory motion to said shaft, a bearing for said sleeve, and means for lubricating said eccentric sleeve including an oil receptacle fixed on said shaft and having an open mouth, said receptacle having a cover resting on the edge of the receptacle, the bearing surface of the cover being a portion of a sphere having the center of gyration of the shaft as a center.

22. A gyratory crusher, comprising in combination, a frame, a shaft supported for gyratory motion about a point, a rotary eccentric sleeve for imparting gyratory motion to said shaft, a bearing member supporting said sleeve and having two downwardly extending portions the adjacent walls of which are cylindrical and coaxial, and means for lubricating said eccentric sleeve including an oil receptacle fixed on said shaft, the cylindrical wall of which extends upwardly between the downwardly extending portions of the bearing member, and a dust cap for said receptacle consisting of an annular member having its lateral edges slidably fitting against the adjacent walls of the bearing and its bottom resting on the edge of the oil receptacle.

23. A gyratory crusher, comprising in combination, a frame, a shaft supported for gyratory motion about a point, a rotary eccentric sleeve for imparting gyratory motion to said shaft, a bearing member supporting said sleeve and having two downwardly extending portions the adjacent walls of which are cylindrical and coaxial, and means for lubricating said eccentric sleeve including an oil receptacle fixed on said shaft, the cylindrical wall of which extends upwardly between the downwardly extending portions of the bearing member, and a dust cap for said receptacle consisting of an annular member having its lateral edges slidably fitting against the adjacent walls of the bearing and its bottom resting on the edge of the oil receptacle, said bottom having a spherical bearing surface centered about the center of gyration of the shaft.

24. A gyratory crusher, comprising in combination, a frame, a shaft supported for gyratory motion about a point, a rotary eccentric sleeve for imparting gyratory motion of said shaft, a bearing member sup-

- porting said sleeve and having a downwardly extending portion, the inner wall of which is cylindrical, and means for lubricating said eccentric sleeve including an oil receptacle fixed on said shaft, the cylindrical wall of which extends upwardly above the lower end of said sleeve, and a dust cap for said receptacle consisting of an annular member having its circular outer edge slidably fitting against the cylindrical wall of the bearing and its bottom slidably resting on the edge of the oil receptacle.
25. A gyratory crusher comprising in combination, a shaft adapted for gyratory movement about a point adjacent its lower end, a rotatable eccentric engaging the upper end of said shaft, and means for oiling the bearing surfaces of said eccentric including an oil receptacle mounted on the shaft the walls of which extend upward above the lower end of the eccentric, and means fixed against lateral movement for closing the mouth of said receptacle against the entrance of dust.
26. A gyratory crushing machine including in combination, a frame, a vertical shaft adapted to be gyrated above a point adjacent its lower end, a cap removably secured to said lower end of the shaft and arranged to transmit the weight of the shaft to the frame and also to bear the lateral thrust of the shaft on the frame.
27. A gyratory crusher including in combination, a frame, a vertical shaft mounted in said frame and adapted to be gyrated about a point adjacent its lower end, a cap removably secured to its lower end and arranged to transmit the weight of the shaft to the frame and to transmit the lateral thrust of the shaft to the frame, said cap having a cylindrical outer surface.
28. A gyratory crusher including in combination, a frame, a vertical shaft mounted in said frame and adapted to be gyrated
- about a point adjacent its lower end, a cap ⁴⁵ removably secured to its lower end and arranged to transmit the weight of the shaft to the frame and to transmit the lateral thrust of the shaft to the frame, said cap having a cylindrical outer surface and a ⁵⁰ tapered axial recess to receive the end of the gyratory shaft.
29. A cap for the end of a gyratory crusher shaft having a recess to receive the end of the shaft, a surface to transmit lateral thrust of the shaft to a frame, and a surface to transmit the weight of the shaft to a frame, said cap being removable from the shaft.
30. The combination with the shaft of a ⁶⁰ gyratory crushing machine having a tapered end, of a protective cap having surfaces for transmitting lateral thrust and vertical thrust from the shaft to the frame, said cap being removable from said shaft. ⁶⁵
31. The combination with the shaft of a gyratory crushing machine, of a protective cap for the end of said shaft said cap having a recess to receive the shaft, a cylindrical outer surface and an end bearing surface, said cap being removable from the shaft and having an aperture in its end for the insertion of a tool to contact with the end of the shaft to effect its separation therefrom. ⁷⁰ ⁷⁵
32. A gyratory crushing machine including in combination, a frame, a crushing cone movably supported in the frame, and a crushing hopper surrounding the cone and secured to the frame, said hopper flaring ⁸⁰ toward both ends from an intermediate point and said hopper being divided circumferentially into a plurality of sections, one of said sections being wedge-shaped for the purpose set forth. ⁸⁵

In testimony whereof I hereunto affix my signature.

WILLIAM STEVENSON WESTON.
